Primary Examiner — Michael C Stout*Assistant Examiner* — Katrina N Gonzalez(74) *Attorney, Agent, or Firm* — Bay State IP, LLC(57) **CLAIM**

The ornamental design for a pet carrier, as shown and described.

DESCRIPTION

FIG. 1 is a front perspective view of the pet carrier showing our new design;

FIG. 2 is a front view thereof;

FIG. 3 is a back view thereof;

FIG. 4 is a right side view thereof;

FIG. 5 is a left side view thereof;

FIG. 6 is a bottom view thereof; and,

FIG. 7 is a top view thereof, but shown open in a configuration of use for clarity of illustration.

The broken lines shown in FIG. 6 illustrate portions of the pet carrier that form no part of the claimed design.

1 Claim, 7 Drawing Sheets(56)
